UNITED STATES PATENT OFFICE.

JOSE R. C. RUYBAL, OF ALAMOSA, COLORADO.

BASE FOR POSTS.

Application filed January 14, 1922. Serial No. 529,136.

To all whom it may concern:

Be it known that I, JOSE R. C. RUYBAL, a citizen of the United States, and a resident of Alamosa, in the county of Alamosa, and State of Colorado, have invented certain new and useful Improvements in Bases for Posts, of which the following is a specification.

My invention relates to bases for posts, and has reference more particularly to reinforced cement bases for fence posts, corral posts, stock yard posts, and for all kinds of poles supporting electric wires and the like.

An object of the invention is to provide a base for posts which will be indestructible and unaffected by the elements.

Another object is to provide permanent bases for wooden posts to which panel fencing or wire fencing can be readily attached and which can be just as readily removed.

Another object is to provide a base with which can be utilized woods which are frequently allowed to go to waste because of no other profitable use.

Another object is to provide a base to which wooden posts can be readily applied and which will prevent the said wooden posts from rot and decay.

With these and other objects in view, my invention consists in certain novel features of construction, arrangement and combination of elements as will be hereinafter fully described and pointed out in the claims, reference being had to the accompanying drawings forming a part hereof in which,

Figure 1 is a perspective view of a base according to my invention, the fence post being indicated in broken lines,

Figure 2 is a similar view of a base having round form,

Figure 3 is a vertical section,

Figure 4 is a view showing reinforcing elements,

Figure 5 is a transverse section on the line 5—5 of Figure 1, showing the disposition of the reinforcing means,

Figure 6 is a view of one of the post attaching plates, and

Figure 7 is a transverse section on the line 7—7 of Figure 2.

Figure 8 is a view of modified form of reinforcing element,

Figure 9 is a view showing another modification of same,

Figures 10, and 11 are perspective views showing application of these modifications to square and round bases respectively, and their attachment to square and round posts respectively,

Figures 12, 13, and 14 are views showing other modifications and means of connecting posts and base.

In carrying my invention into effect, I provide a base 10 which is preferably tubular and is molded from cement and sand mixed in the proper proportions. The general cross sectional shape may be polygonal as shown in Figures 1 and 5, or it may be circular as shown in Figures 2 and 7.

The base includes a shank portion 10, a cap portion 11 and a foot 12 which are formed by casting the shank with annular flanges. The cap or head flange has its upper and lower faces beveled and converging as clearly shown in Figures 1, 2 and 3, the upper face being beveled downwardly so that water will shed therefrom.

The foot flange has its lower face flat, and its upper face beveled, and as the flange projects laterally some distance beyond the shank or body portion, it will form an anchorage in the earth for the base when embedded therein.

I provide these bases with reinforces which are introduced in the mold or form in which the base is cast, so that it is embedded therein and securely interlocked when the base hardens and sets.

This reinforcing is made of a fabric consisting of horizontal wire strands or cables 13, any suitable number being used.

The vertical members of the woven wire reinforcing fabric comprises a pair of loops 14, which when the whole is rolled into shape and set into the base will be diametrically opposite each other as indicated in Figures 1, 2 and 3, they extending above the head of the base.

The loops are made of wire twisted into cable form and the upper portion includes three strands, one strand extending about six inches into the base as indicated by 15, the second strand extending about fifteen inches into the base and indicated by 16, and

the last strand runs clear down into the foot of the base, this strand being indicated by 17. All of these strands are of course interwoven or interlocked with the horizontal strands 14.

To provide means for attaching a wooden post to the base, I provide two plates, each having a body portion 18 of substantially rectangular shape and a triangular shaped wing 19. The member 18 is provided with several openings 20 (three in the present instance), and the wing 19 is also provided with a similar opening 21 positioned adjacent the apex of the triangle, all as clearly shown in Figure 6.

The plates are grooved at the junction of the body and the wing as indicated by 22, and the wings are bent inwardly along the line of junction embracing the loops 14 which are left projecting beyond the head of the base members.

The wings are then forced against the body portion 18 whereupon the opening 22 will register with the central opening of said plate 19.

The wooden fence post 23 is now placed on the top of the base with its lower end flat thereon and screws or bolts 24 are driven through the openings in the plates and wings into the wooden post and thus fasten it securely to the loops and into the base.

If a polygonal fence post is used, the plates will be flat as shown in Figure 1, while if a round post is used the attaching plates will be curved as shown in Figure 2.

The shank and foot can be made solid throughout their extent in these bases, or they may be made partly tubular, the latter form insuring extreme lightness and at the same time possessing great strength.

The strength of the complete assembly can be increased by increasing either the reinforcement or by increasing the proportion of cement to sand, or by increasing both. While the structure shown in Figure 2 is primarily intended to take a round post, it is obvious that it will take a flat or a square wooden post and the plates will hold it securely in place.

In Figure 8 I have shown a modified form of reinforcing element which comprises wires bent to form loops 30 spaced apart and the wires being twisted together to form a thick stem 31, and the lower ends of the wires extending radially outwardly from the same as indicated by 32.

This form is molded into the base 33 shown in Figure 10 with the loops 30 extending upwardly from the base 37, and secured to the post 34 indicated by dash lines, by staples 35 driven into the said post 34. The post may be centered on the base, and additionally held by the metal point 36 firmly embedded in the upper end of the base.

In Figure 9 the reinforcing and securing element is substantially the same as in Figure 8 comprising as it does the loops 40, the stem 41 and the radiating lower ends 42, but in this form the wires of the stem 70 at about its longitudinal center are not twisted together but are expanded or bulged laterally to form a loop 43. This form may be used with either a round base and post or a square base and post, but if used with 75 a base and post as shown in Figure 11, the loops are preferably bent inwardly and crossed standing diagonally as shown in Figure 11 and then secured to the post by staples 44 as shown. The base 45 may also 80 be provided with the metal point 46 as in the form shown in Figure 10.

In Figure 12 the reinforce wires 50 extend up from the base and have small eyes or openings through which are driven 85 spikes 52 into the post. These wires are additionally held in place and clamped to the post 54 by the split clamp rings 55 the ends of which are drawn together by screw bolts 56.

In Figure 13 the reinforcement loops 60 are secured to the post 61 by the staples 62 and are held and clamped thereto by the split clamp rings 63 secured by a screw bolt 64.

In Figure 14 the reinforce loops 60 is similarly secured by staples 62 but they are additionally held and clamped by wire strands 65 wrapped around them and the post in two bands.

The bases herein set forth can be used to support electric line poles, and will form practically a perpetual base for such poles. For such use however, it is advisable to increase the number of cables forming the 105 reinforce.

With my improved base many of the poplars, cottonwood trees, willows, etc., which go to waste can be used to advantage for telephone poles, poles for other electric installations, and fence posts. Indeed a farmer can raise such trees and other fast growing trees for timber for the above mentioned uses.

I claim:

1. In a device as herein set forth, the combination of a body portion or shank, fastening devices embedded in the shank and having looped ends extending above the top of the shank at opposite sides thereof, a 120 post adapted to be seated at the upper end of the shank and between said looped ends, means for securing said looped ends to the post, and a metal point projecting upwardly from the top of the shank to additionally 125 secure the post in place.

2. In an artificial stone or cement post base, the combination of a shank or body portion, fastening devices embedded in the shank and having looped ends extending 130

above the top of the shank, a post adapted to be seated at the upper end of the shank, and means for securing the said looped ends to the post, said means comprising a plate 5 of sheet metal hingedly connected to the cross bars of said loops and provided with nail receiving perforations.

3. In an artificial stone or cement post base, the combination of a body portion or 10 shank, fastening devices embedded in the

same and having looped ends extending above the top of the shank, and means for securing said looped ends to a post, said means comprising a plate of sheet metal provided with nail receiving perforations 15 and folded upon itself to provide a hinge connection with the said loops, for the purpose specified.

JOSE R. C. RUYBAL.
